THERMOSTAT

Earl K. Clark, Mansfield, Ohio, assignor to Westinghouse Electric & Manufacturing Company, East Pittsburgh, Pa., a corporation of Pennsylvania

Application October 21, 1938, Serial No. 236,226

7 Claims. (Cl. 200—122)

My invention relates to thermostats and more particularly to a high-wattage, bimetallic snap-acting thermostat.

An object of my invention is to provide a bimetallic thermostat having a resilient adjusting member engaging the bimetallic member and exterior adjusting means so as to eliminate any back-lash between the exterior adjusting means and the bimetallic member to ensure critical adjustments therebetween.

A further object of my invention is to provide a range-oven thermostat which may be directly associated with the oven and the power supply therefor without the use of additional relays and controlling mechanisms.

A still further object of my invention is to provide a bimetallic thermostat having a movable contact assembly rigidly attached to, and insulated from, the bimetallic member, a heater being provided which permits the thermostat to handle at least 4,000 watts and further enables such thermostat to operate with a two to one ratio and temperature amplitude, or less, from the center of the oven to the bimetallic member.

Another object of my invention is to provide a simple, rugged, inexpensive, sensitive, direct-operating range-oven thermostat which will carry the complete oven load and maintain an oven temperature differential of substantially 30° F. throughout the complete oven temperature range.

Other objects of my invention will either be pointed out specifically in the course of the following description of the device embodying my invention or will be apparent from such description.

In the accompanying drawing:

Figure 1 is a top plan view of a device embodying my invention, with the top cover thereof removed;

Fig. 2 is a partial side sectional view of the device embodying my invention with the cover thereof in place;

Fig. 3 is an enlarged top view of the bimetallic member included in the device shown in Figs. 1 and 2;

Fig. 4 is a side elevational view of the bimetallic member shown in Fig. 3 with an attaching bracket rigidly attached thereto;

Fig. 5 is a partial sectional view taken along the line V—V of Fig. 2;

Figs. 6, 7 and 8 are top, end and side views, respectively, of the adjusting member included in the device shown in Figs. 1 and 2, Fig. 6 being taken in a plane at right angles to fingers 68;

Fig. 9 is an enlarged view taken along the line IX—IX of Fig. 2; and

Fig. 10 is a perspective view of the adjusting member of Figs. 6, 7 and 8.

Referring to the accompanying drawing, I show a bimetallic range oven thermostat 10

comprising a casing or supporting structure 12, a bimetallic member 14, an adjusting member 16 rigidly attached to the supporting structure 12 and engaging the bimetallic member 14, an arm 18 operatively associated with the supporting structure 12 and engaging the adjusting member 16, an exterior adjusting means 20 operatively associated with the supporting structure 12 and the arm 18 for adjusting the bimetallic member 14, movable contact assembly 22 including U-shaped bracket 24 actuated by bimetallic member 14, contact plate 26 and heater 28 in thermal communication with the bimetallic member 14, and stationary contacts 30 positioned on, and insulated from, the supporting structure 12.

The casing or supporting structure 12 comprises in this instance a box-like base 32 and a removable cover 34. The base 32 is preferably formed from light sheet metal into an elongated parallelopiped having an open-top. A plurality of elongated slots 36 are formed within the bottom surface and adjacent side portions of the box 32 located at one end thereof to permit free passage of heated air therethrough. The box 32 may be constructed in any suitable fabricated manner; however, it is to be understood that such structure must be formed so as to adequately support the bimetallic structure, as hereinafter described.

A removable top 34, adapted to be readily placed upon the support 12, consists primarily of an elongated sheet metal strip having a downwardly extending flange 38 at one end and a plurality of upwardly extending lugs 40 at the other end thereof. A boss 42 is located on the depending flange 38 to cooperate with the supporting structure and to retain the cover thereon. The removable top 34 is positioned upon and attached to the box 32 by inserting the lugs 40 within suitable slots 44 in the upper end of structure 32, and by snapping the inwardly extending boss 42 located upon the depending end portion 38 into the cooperating aperture 46 at the other end of the structure 32. Suitable slots 38a, in addition to slots 36, are also positioned within one end of the cover 34 to further permit passage of heated air through the supporting structure 12.

The bimetallic member 14 comprises, in this instance, a unitary member having elongated slots 48 therein which form a central strip 50 and two exterior strips 52 as well as end portions 54 and 56. However, it is to be understood that the bimetallic member 14 may be formed of a plurality of members rigidly attached together so as to form a similar functionally integral structure. The central strip 50 has positioned along its outer edge, substantially at the mid-points thereof, inwardly extending notches 58 which cooperate with the adjusting member 16 in a

manner hereinafter described. An aperture 58 is located in the end portion 54 of the bimetallic member 14 to permit a supporting angular bracket 60 to be rigidly attached thereto by means of a suitable rivet 62, substantially as shown in Fig. 4. This angular bracket is rigidly attached to the bimetallic member 14 in line with the teachings of E. K. Clark and P. R. Lee in a copending application, Serial No. 225,354, filed 10 August 17, 1938, and assigned to the assignee of the present application.

The rivet 62 is rigidly attached to the bimetallic member before the heat treatment thereof and may then be heat treated along with the bimetallic member 14. The bimetallic member 14 may thus be rigidly attached to the supporting structure 12 without altering the thermal characteristics thereof in any manner whatsoever. An aperture 64 is located within the second end 20 portion 56 of the bimetallic member 14 to permit the movable contact assembly 22 to be rigidly attached thereto, as hereinafter described.

The intermediate adjusting member 16 is preferably formed from a single sheet of resilient material and includes a main body portion 66, two upwardly extending fingers 68, positioned substantially normal to the main body portion, and an upwardly extending post 76 positioned intermediate the fingers 68. The body portion 30 66 has a plurality of apertures 70 located in one end thereof to permit adjusting member 16 to be rigidly attached to the supporting structure 12 by means of rivets 72, as shown in Fig. 2. The fingers 68 have outwardly extending notches 74 35 positioned on their inner edge at substantially the upper end thereof to cooperate with the bimetallic member 14. The exact shape of these fingers and the manner of cooperation with the bimetallic member 14 is more fully described and 40 is claimed in my copending application Serial No. 237,270, filed October 27, 1938, and assigned to the assignee of the present application.

The fingers 68, being formed of resilient material, may be forced outwardly, so as to permit 45 a snap-on resilient fulcruming engagement with the central strip 58 of the bimetallic member 14, as hereinafter more fully described.

The upwardly extending post 76 is substantially triangular with the vertex positioned above the 50 main body portion 66 of the adjusting member 16. An elongated boss or ridge 77 is formed within the post to give it additional strength. Small triangular notches are cut within the vertex of the triangular post so as to form small 55 ledges 78, one on either side of an upwardly extending tongue 81. The ledges 78 and tongue 81 cooperate with lip 82 of the arm 18 to permit the adjusting movements thereof to be directly transmitted to the main body portion of the 60 adjusting member 16 without distorting the fingers 68.

The arm 18 comprises, in this instance, substantially a channel-like member, see Figs. 1, 2 and 5, having a flat top portion 78, downwardly 65 extending side portions 88 and an outwardly extending lip 82 which is substantially in the plane of the top surface 78 and located at one end thereof. The arm 18 is fulcrumed to the casing or support 12 by means of a through-pin 84 70 which extends through the depending side portions 80 of the arm 18 and the side walls of the casing 12 to permit the arm 18 to rotate about the pin 84. This action permits the arm 18 to transmit the manually adjusted movements of 75 the adjusting means 20 to the bimetallic mem-

ber 14, through the cooperative action of the intermediate adjusting member 16 and lip 82. The lip 82 extends outwardly from the top surface 78 of the arm 18 and is fitted over tongue 81 of post 76 so as to transmit the movements of the 5 arm 18 to the fingers 68, in a manner herein-after more fully described. A large rectangularly-shaped aperture 86 is positioned within substantially the left end portion of the arm 18 to permit the movable contact assembly 22 to extend therethrough as shown in Figs. 1, 2 and 5, and as hereinafter described.

The adjusting means 20, as shown in Fig. 2, includes in this instance a threaded shaft which extends through the bottom surface of the casing 12 and cooperates with an abutment 88 located at substantially the right end of arm 18. The adjusting screw 20 is threadedly attached to the supporting structure 12 by means of an internally threaded bushing 90 which is rigidly 20 attached to such casing 12 by having its upper ends riveted over tightly against the inner surface of such structure.

A small pin 91 is positioned close to the bushing 90 and is rigidly attached to the supporting 25 structure 12. A stop lug 93 is positioned upon and adjustably attached to the screw 20. This lug is attached to the screw 20 so that it will contact the pin 91 and limit the rotational movement of such screw as it is rotated within the 30 bushing 90. The cooperation of the pin 91 and lug 93 thus prevents the screw from being accidentally removed or from being run in so far as to injure the thermostat.

The movable contact assembly 22, more fully 35 described in my above-identified copending application, comprises a U-shaped bracket 24, a contact plate 26 flexibly attached to the bracket 24, contacts 82 insulatedly attached to the contact plate 26, and a radiant heater 28 bent into substantially U shape and rigidly attached to the contacts and to contact plate 26 and insulated therefrom. The contact assembly 22 is rigidly attached to the free end of the bimetallic member 14 by means of a rivet 88 which extends 40 through the aperture 64 in the bimetallic member 14.

In assembling the thermostat embodying my invention, the resilient intermediate adjusting member 16 is rigidly attached to the inner bottom surface of the box-like supporting structure 12 by means of rivets 72 as hereinabove described, whereupon the fingers 68 and post 76 will extend substantially upwardly. The arm 18 will now be positioned within the support 12 so that 55 the aperture 86 in lip 82 will cooperate with the ledges 78 and tongue 81 of post 76 of adjusting member 16 and the through-pin 84 will be inserted through the arm 18 and the side walls of the casing 12 to fulcrumly mount such arm 60 thereabout. The arm 18 will then be operatively associated with the supporting structure 12 and the adjusting member 16 through the cooperation of the pin 84 and lip 82.

The bimetallic member 14, having previously 65 had the angular bracket 60 and movable contact assembly 22 rigidly attached thereto and having been properly heat treated to its predetermined value, is positioned within the supporting structure 12 in such a manner that the central strip 58 thereof will cooperate with the upwardly extending fingers 68 of resilient adjusting member 16 (so that the notches 74 located in central strip 58 will cooperate with notches 74). The bimetallic member is then forced downward- 75

ly, whereupon the fingers 68 will expand outwardly, permitting a resilient snap-on fulcruming action therebetween. The angular bracket 60 is then forced downwardly permitting the screw 98 to be inserted within the end wall of the supporting structure 12 to cooperate with the threaded aperture 100 in the bracket 60. Suitable bosses 101 may be formed within the end of the supporting structure, which, along with the slot 103 positioned in the bottom of the structure to receive tongue 105 of bracket 60, maintains the bracket in alignment therewith. The bimetallic member 14 is then rigidly attached at one end thereof to the supporting casting 12 and engages the adjusting member 16 or, more specifically, the central strip of the bimetallic member 14 engages the adjusting member and cooperates with the arm 18 through such member.

20 The resilient adjusting member 16 biases the bimetallic member 14 and the arm 18, at its left end, upwardly at all times due to its inherent characteristics and to the particular shape of its main body portion 66 thereof. The adjusting screw 20 is then threadedly inserted within the bushing 90 which has been rigidly attached to the supporting structure 12 so as to engage the abutment 88 which, due to the cooperative action of the resilient adjusting member 16, is biased in a downward direction. The adjusting screw 20 is, however, run into the supporting structure a considerable distance further so that the arm 18 is in a substantially horizontal position at the mid-point of the temperature range of the thermostat.

25 With the adjusting screw 20 holding the arm 18 in substantially a horizontal position and with resilient intermediate adjusting member 16 biasing the left end of the arm 18 upwardly or away from the horizontal position, it is apparent that there will be a positive action between the lip 82 and post 76 of resilient adjusting member 16, and between abutment 88 and adjusting screw 20 at all times. Accordingly, the back-lash in the threaded cooperation between the adjusting screw 20 and bushing 90 will be eliminated and a positive engagement between the resilient member 16 and arm 18 will be maintained at all times.

30 Due to the apparent concave upwardly curvature of the bimetallic member 14 as shown in Fig. 4, after such member has been heat treated, it follows that with the cooperative action of the outwardly extending notches 74 of fingers 68, such fingers retain the bimetallic member 14 in substantially a horizontal position at the mid-point of the temperature range. In addition there will be at all times a positive connection or engagement therebetween. Accordingly, it is obvious that due to the cooperative engagement between the adjusting member 16 and the arm 18 there will be a positive connection between the adjusting screw 20 and the bimetallic member 14, at all times, whereby any adjusting movements whatsoever of the adjusting screw 20 will be immediately transmitted to the bimetallic member 14 without any idle or lost motion.

35 The contact assembly 22, rigidly attached to the free end of the bimetallic member 14 through the cooperation of rivet 96 with aperture 64, extends downwardly within the rectangular aperture 86 in arm 18. The substantially U-shaped heater 28 then extends along under the bimetallic member 14 away from the adjusting screw 20 so as to be in thermal communication

with the bimetallic member 14. With the bimetallic member 14 rigidly attached at one end thereof to the supporting structure 12, as hereinabove described, and with the movable contact assembly rigidly attached to the lower surface of the free end of the bimetallic member, it follows that such movable contact assembly 22 will positively engage with the stationary contacts 30 to afford a good electrical contact therewith as the bimetallic member 14 is in its lower or operative position.

An angular bracket 102 or any other suitable structure is attached to the side wall of the supporting member 12 by means of screw 104 and extends out over the free end of the bimetallic member 14 so as to cooperate with the upper surface of the rivet 86. The angular bracket 102 thus limits the upward movement of the bimetallic member 14, whereas cooperation with the stationary contacts 30 limits the lower movement thereof. However, it is to be understood that the movements of the free end of the bimetallic member 14 are to be very limited, being of the order of $\frac{1}{100}$ of an inch.

In the manual adjustment of the thermostat embodying my invention, assuming that the bimetallic member is in an open or disengaged position, the free end of the bimetallic member 14 and the movable contact assembly 22 will be in an upper position with the top portion of rivet 96 engaging the angular bracket 102. However, through the cooperative engagement of the central strip 50 with the fingers 68, the central portion of the bimetallic member 14 will be retained in its predetermined position. The exact location of this position determines the opening and closing temperatures of the bimetallic member, inasmuch as the bimetallic member must snap about the fulcruming engagement between the fingers 68 and the central strip 50 in a manner described in my above-identified copending application.

Should it be desired to adjustably lower these operating temperatures with the bimetallic member 14, the adjusting screw 20 will be rotated so that the right end of the adjusting arm 18 is raised. Inasmuch as the arm 18 is fulcrumed intermediate the ends thereof, the lip 82, located at the other end of the arm 18, will be lowered, causing the fingers 68 and post 76 which cooperate therewith, to be likewise lowered. The retained or engaged portion of the central strip 50 of the bimetallic member 14 will then, in a similar manner, be lowered with the fingers 68, thus lowering the "off" and "on" operating temperature of the bimetallic member 14.

It is, therefore, obvious that the adjusting screw or adjusting means 20 operatively associated with the support 12, through the sleeve 90, and the arm or second intermediate member 18, through abutment 88, adjusts the operation of the bimetallic member 14 through the cooperative action of the resilient intermediate adjusting member 16 and its engagement with the bimetallic member 14.

When operating the thermostat embodying my invention within the oven of a range, the end of the casing in which the bimetallic member 14 is rigidly attached and in which the slots 36 and 36a are positioned, is located within the oven proper, whereas the end of the support 12 containing the adjusting screw 20 is located or positioned outside of the walls of the oven. The adjusting screw 20 is thus located outside of the

heated oven so that such screw and cooperating sleeve 90 will be relatively cool with respect to the bimetallic end of the thermostat. Such arrangement will prevent any galling action between such adjusting screw and sleeve.

It is further obvious that with the bimetallic member 14 located in the oven proper, as mentioned above, such bimetallic member will receive heat directly from the oven without the use of any additional relays or bimetallic thermostat. However, inasmuch as the bimetallic member 14 will be located substantially close to one wall or side of the oven, the temperature thereof would tend to be slightly lower than the central point of the oven. However, due to the thermal communication between the heater 28 and the bimetallic member 14, the temperature of such bimetallic member 14 will be maintained substantially the same as the temperature of the midpoint of the oven without an appreciable time lag. In other words, the bimetallic member 14 responds jointly to the heat from the center of the oven and from the heater 28. Accordingly, the thermal amplitude or heat range of the oven will be greatly reduced by ensuring a relatively quick heating of the bimetallic member 14, when power is being supplied to the oven heaters (not shown). The thermostat embodying my invention will thus not only reduce the thermal amplitude of the oven during continued operation thereof, but will eliminate to a great extent the initial temperature "overshoot" when the oven is first connected to the power supply (not shown) by an operator.

35 Inasmuch as the movable contact assembly 22 is formed in the manner hereinabove described, it follows that such thermostat may carry the total operating current of the oven without the need of additional power or current relays.

40 Various modifications may be made in the device embodying my invention without departing from the spirit and scope thereof, and I desire, therefore, that only such limitations shall be placed thereon as are imposed by the prior art and the appended claims.

45 I claim as my invention:

1. A thermostat comprising, in combination, a supporting structure, a bimetallic member, an intermediate adjusting member having two spaced parts for resiliently engaging the bimetallic member, an arm operatively associated with the support and having one portion disposed between the parts of the intermediate member, and an adjusting means directly associated with the arm for adjusting the operations of the bimetallic member through the cooperative actions of the arm, intermediate member and bimetallic member.

2. A thermostat comprising, in combination, a supporting structure, a bimetallic member, an intermediate adjusting member having two spaced parts engaging the bimetallic member, an arm rockably attached to the support and engaging the adjusting member between said parts, and external adjusting means operatively associated with the support and arm for varying the operations of the bimetallic member.

70 3. A thermostat comprising, in combination, a supporting structure, a functionally integral bimetallic member having a central strip and two exterior strips, and an adjusting member attached at substantially one end to the support and having two spaced parts engaging the cen-

tral strip of the bimetallic member at the other end, an arm attached to the support and engaging the adjusting member intermediate said parts thereof, and external adjusting means operatively associated with the support and arm for varying the operations of the bimetallic member. 5

4. A thermostat comprising, in combination, a supporting structure, a bimetallic member, a resilient intermediate adjusting member having fingers for yieldingly engaging the bimetallic member, an arm attached to the support and engaging the fingers, and external adjusting means operatively associated with the support and arm for varying the operations of the bimetallic member. 10

5. A thermostat comprising, in combination, a supporting structure, a bimetallic member, a resilient intermediate adjusting member rigidly attached to the support at one end and having fingers on the other end which fulcrumly engage 20 the bimetallic member, a second intermediate member rockably attached to said structure and engaging the fingers, and adjusting means operatively associated with the support and second intermediate member for adjusting the operations of the bimetallic member. 25

6. A thermostat comprising, in combination, a supporting structure, a functionally integral bimetallic thermal responsive member having a central strip and two exterior strips rigidly attached at substantially one end to the support, a resilient intermediate adjusting member attached at one end to the support having fingers on the other end which resiliently engage the central strip of the bimetallic member, a second intermediate member operatively associated intermediate the ends thereof with the support and operatively associated at one end with the fingers, and adjusting means operatively associated with the support and the second end of the intermediate member for adjusting the operations of the bimetallic member through the cooperative actions of the second intermediate member, intermediate adjusting member and the central strip of the bimetallic member. 30 35

7. A thermostat comprising, in combination, a supporting structure, a functionally integral bimetallic thermal responsive member having a central strip and two exterior strips rigidly attached at substantially one end to the support, a movable contact assembly attached to and movable with the free end of the bimetallic member including a contact plate, contacts insulatedly attached to the plate and a heater attached to the contacts and in thermal communication with the bimetallic member, a resilient intermediate adjusting member attached at one end to the support having fingers on the other end which resiliently engage the central strip of the bimetallic member, a second intermediate member operatively associated intermediate the ends thereof with the support and operatively associated at one end with the fingers, and adjusting means operatively associated with the support and the second end of the intermediate member for adjusting the operations of the bimetallic member and movable contact assembly through the cooperative actions of the second intermediate member, intermediate adjusting member and the central strip of the bimetallic member. 40 45 50 55 60 65 70

EARL K. CLARK.
